(57) **CLAIM**

The ornamental design for a pot clip, substantially as shown and described.

DESCRIPTION

FIG. 1 is a perspective view of a pot clip, according to the present invention;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a side elevational view thereof; the opposite side elevational view being identical.

The broken lines in the figures illustrate the portions of the design that form no part of the claimed design.
